[57] CLAIM

The ornamental design for paint brush holder, as shown and described.

DESCRIPTION

FIG. 1 is a perspective view of a paint brush holder showing my new design, with the fragmentary showing of a paint can and brush in broken lines for illustrative purposes only and forming no part of my claimed design.

FIG. 2 is a front elevational view thereof.

FIG. 3 is a side elevational view thereof;

FIG. 4 is a rear elevational view; and

FIGS. 5 and 6 are top and bottom plan views, respectively.

FIG. 1

FIG. 5

FIG. 2

FIG. 3

FIG. 4

FIG. 6
